UNITED STATES PATENT OFFICE

2,508,721

AUTOMOBILE WATER HEATER

Robert Ladue, Minneapolis, Minn.

Application October 18, 1946, Serial No. 704,263

3 Claims. (Cl. 219—38)

1

This invention relates to a heating device and particularly to an electrical heating device adapted to be used to heat an internal combustion engine. Such engines are now commonly used in automobiles, and as is well known, trouble is often had in starting automobiles after they have stood in very cold weather. Such internal combustion engines comprise a cylinder block having a water chamber therein. It is desirable to keep the water in said water chamber rather warm. Such cylinder blocks also commonly have bores formed therein extending to the water chamber in which is disposed a bushing having means which will yield in case the water should freeze. Breakage of the block due to the expansion of the freezing water is thus prevented.

It is an object of this invention to provide a simple and efficient heating means for the water in the water chamber, which means is effectively supported and positioned by one of said bushings.

It is further an object of the invention to provide a heating device for the water in the water chamber of a cylinder block of an internal combustion engine comprising a bushing or plug inserted in a bore of said block, a member having a portion extending through a bore in said bushing into said water chamber, a spacing member carried by and secured to said portion adapted to engage said bushing to determine the distance said portion projects into the water chamber, means preferably being provided to secure said bushing to said portion, an electrical heating means in said portion, said member having a second portion disposed outwardly of said bushing, spaced contacts carried by said second portion to which said heating means is connected, a conductor cord having a pair of conductors connected respectively to said contacts and being adapted to be connected to a source of electric current.

It is more specifically an object of the invention to provide such a device as set forth in the preceding paragraph, said first mentioned portion preferably being cylindrical, said spacing member being preferably in the form of a washer surrounding said cylindrical portion and said second portion being provided with a cover preferably of cylindrical form and having an opening through which said cord projects.

2

These and other objects and advantages of the invention will be fully set forth in the following description made in connection with the accompanying drawings in which like reference characters refer to similar parts throughout the several views and in which:

Fig. 1 is a horizontal section through a portion of a cylinder block of an internal combustion engine showing the device of the invention installed therein, said device being shown in plan;

Fig. 2 is a vertical section taken substantially on line 2—2 of Fig. 1, as indicated by the arrows, some parts being shown in side elevation; and

Fig. 3 is a vertical section taken on line 3—3 of Fig. 2, as indicated by the arrows.

Referring to the drawings, a portion of a cylinder block 10 of an internal combustion engine is shown showing the side wall 10a, a pair of cylinders 10b and a portion of the water chamber 10c. The wall 10a is provided with a boss 10d which is bored to receive a bushing or plug 11. Bushing 11 is of cup-shape form having its open side directed outwardly and normally such a bushing has a part adapted to yield under pressure.

In accordance with the present invention said bushing 11 is bored so as to receive the portion 12a of a member 12. A spacing member 13 is provided and while this might be variously formed, in the embodiment of the invention illustrated it is shown as a washer surrounding portion 12a, which portion is preferably cylindrical, and said washer will be secured to portion 12a in any suitable manner, as by welding, soldering or brazing. Member 13 is provided to determine

the distance portion 12a projects into the chamber 10c. It will thus be positioned at different points along portion 12a. Bushing 11 is preferably secured to portion 12a and this can be done by soldering or welding, as indicated by the metal

14. Disposed within portion 12a is an electrical heating means 15 which will usually be in the form of a coil, as indicated in Fig. 2. Member 12 has an outer portion 12b and a pair of spaced contact members 16 are secured to portion 12b.

The ends of heating coil 15 are connected respectively to contact 16. Members 16 are in the form of binding posts having nuts 17 threaded thereon and said posts have respectively connected thereto and between said nuts the conductors 18 contained in a conductor cord 19 which

will be equipped at its other end with the usual plug so as to be plugged into an electrical socket forming a source for electric current. Portion 12b is provided with a cover 20 and while this might be variously formed, it is shown as cylindrical and fitting over portion 12b and having its end spun over a collar or annular rib 12c on member 12. The cover 20, which is made of rather thin metal, has a semi-spherical outer end having a central aperture therein in which is disposed a bushing 21 preferably made of non-conducting material. Cord 19 passes through bushing 21. Cover 20 is preferably provided with a plurality of circumferentially spaced holes 20a to afford circulation and drainage.

In operation bushing or plug 11 will be removed and the same will be bored so that portion 12a fits therein. Member 13 will now be placed on portion 12a and secured thereon at the desired point. Portion 12a will then be inserted through the bore in bushing 11 and said bushing will be secured to portion 12a by welding, soldering or brazing. The cord 19 will be connected, as shown, and cover 20 positioned on member 12. The portion 12a is now passed through the bore in the wall 10a and bushing 11 is driven into place into said bore. Portion 12a is now disposed in the water chamber 10c and the distance it projects into said chamber is determined by the position of spacing member 13. The cord 19 will now be connected with an electrical socket having the usual 110 volt current. When the car is standing for some time, as overnight, in a cold place or in a cold garage, heat can thus be supplied to the water in the water chamber 10c by the heating element 15. The said water is thus kept at a fairly high temperature so that there is no danger of its freezing and it is preferably kept at a temperature which will render it easier to start the engine or motor.

From the above description it will be seen that I have provided a very simple and yet highly efficient heating means for an internal combustion engine and one which can be very easily and quickly installed. The device is small and compact and is carried by the motor without any objectionable features. The device has been amply demonstrated in actual practice, found to be very successful and efficient and is being commercially made.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. The combination with a cylindrical bushing disposed in the wall of the water jacket of an internal combustion engine cylinder block, said bushing having a bore therein of a cylindrical member having a portion extending through said bore into said water chamber, means securing said portion to said bushing, a second member adapted to be disposed on and connected to said portion adjacent said means for engaging the outer side of said bushing to determine how far said portion projects into said water chamber, said cylindrical member having an enlarged por-

tion extending outwardly some distance from said second member and bushing, the same having an annular rib projecting therefrom adjacent its outer end, an electrical heating means in said first mentioned portion having ends extending to the outer end of said enlarged portion, contacts at said outer end to which said ends are connected, a cord having electrical conductors connected to said contacts, and a cover having an inner end extending over said annular rib and fitting said enlarged portion, said cord passing through said cover.

2. The combination with a cylindrical bushing disposed in the wall of the water jacket of an internal combustion engine cylinder block, said bushing having a bore therein of a cylindrical member having an inner portion extending through said bore into said water chamber and having a larger outer portion extending outwardly some distance beyond the outer end of said bushing and having a projection on its periphery adjacent its outer end, an electrical heating means in said inner portion having its ends extending through the outer end of said outer portion, a second member secured to said inner portion and engaging the outer side of said bushing for determining the distance which said inner portion extends into said water chamber, means securing said cylindrical member to said bushing adjacent said second member, an electrical heating means in said inner portion having ends extending to the outer side of said outer portion, contact members secured to said ends, a cord having conductors secured to said contacts and a substantially closed cover having an inner end extending over said projection and fitting on said outer portion, said cord extending centrally through the outer end of said cover.

3. The combination with a cylindrical bushing disposed in the wall of the water jacket of an internal combustion engine cylinder block, said bushing having a bore therein of a cylindrical member having a portion extending through said bore into said water chamber, a second member connected to said portion and engaging said bushing to determine how far said cylindrical member projects into said water chamber, said cylindrical member having an enlarged outer portion projecting beyond said bushing, an electrical heating means in said cylindrical member having terminals extending to the outer side of said outer portion, contacts secured to said outer side connected to said terminals, a cord having electrical conductors secured to said contacts, a substantially closed cover fitting on said outer portion and enclosing said contacts, said cord passing through said cover and being adapted to have a connecting plug at its outer end.
